(57) **CLAIM**

The ornamental design of a pressurized gas dispenser, as shown and described.

DESCRIPTION

FIG. 1 is a perspective view of the pressurized gas dispenser showing the new design.

FIG. 2 is a right side view of the invention.

FIG. 3 is a left side view of the invention.

FIG. 4 is a rear view of the invention.

FIG. 5 is a front view of the invention.

FIG. 6 is a top view of the invention; and,

FIG. 7 is a bottom view of the invention.

The broken lines shown in the drawings depict portions of the pressurized gas dispenser that form no part of the claimed design.
